UNITED STATES PATENT OFFICE.

MELVILLE CLARK, OF CHICAGO, ILLINOIS, ASSIGNOR TO MELVILLE CLARK PIANO COMPANY, OF CHICAGO, ILLINOIS, A CORPORATION OF ILLINOIS.

AUTOMATIC PIANO-PLAYING MECHANISM.

1,086,276.

Specification of Letters Patent.

Patented Feb. 3, 1914.

Application filed May 27, 1912. Serial No. 699,871.

To all whom it may concern:

Be it known that I, MELVILLE CLARK, a citizen of the United States, residing at Chicago, in the county of Cook and State of Illinois, have invented new and useful Improvements in Automatic Piano-Playing Mechanism, of which the following is a specification, reference being had to the accompanying drawings, forming a part thereof.

The purpose of this invention is to provide an improved construction of mechanism for automatic playing on a piano, dispensing with the necessity for inclosing in the piano case anything except the necessary parts for striking the keys and the pneumatic connections thereto, those parts being so situated in the case as to leave the keys exposed as for hand playing.

It consists in the elements and features of construction shown and described as indicated in the claims.

In the drawings: Figure 1 is a partly sectional plan view of the frame and manual of a grand piano, section being made at a horizontal plane below the string board, showing the position therein relatively to the customary parts of the piano of the pneumatic action and certain other parts. Fig. 2 is a section at the line 2—2 on Fig. 1. Fig. 3 is a vertical fore-and-aft section of a cabinet exterior to the piano case, containing the tracker, note sheet, note sheet rolls and their operating mechanism, and the exhaust mechanism for the pneumatic action which is shown in the piano, Fig. 1. Fig. 4 is a detail plan view of the tracker and duct connections of the structure shown in Fig. 3. Fig. 5 is a detail rear elevation of the duct board and duct connections of said structure. Fig. 6 is an axial section of one of the cable couplings. Fig. 7 is a detail edge view of such coupling. Fig. 8 is a perspective view of a coupling device for connecting the cabled tubes. Fig. 9 is a perspective view of a piano and cabinet and connecting cable embodying this invention.

The drawings show a grand piano of customary form having mounted under the manual keys, 1, pneumatic striker actions consisting of motor or striker pneumatics, 2, having their moving walls connected with thrust pins, 3, for acting on the keys, respectively, when the striker pneumatics are actuated in the usual manner by collapsing

when communication with the exhaust devices is opened.

In the drawings, the structure represented comprises two pneumatic actions, the principal action comprising striker pneumatics, 60 which may be understood to be the full number of the manual keys (eighty-eight) though not fully shown; the other action, hereinafter referred to as the supplemental action, comprising striker pneumatics for 65 only a portion (fifty-two) of the manual keys at a medial portion of the manual comprising the notes likely to be required for playing a solo or melody of a piece of music.

The two pneumatic actions are mounted 70 as a unitary structure upon the under framework of the piano, said actions being assembled so that they can be introduced bodily under the manual of a grand piano of ordinary construction and secured to the frame 75 in any convenient manner, so as to position the thrust pins operatively as described in relation to the respective manual keys.

The principal and supplemental sets of striker pneumatics are mounted in a familiar 80 manner upon shelves or duct boards, 4, which jut off from the vertical walls of the rigidly united primary pneumatic chambers, 5 and 6, of the principal and supplemental actions, respectively; and said striker pneumatics are controlled in their striking action, in the familiar manner, by their respective primary pneumatics, not shown, operating the valves, 6, which at collapsed position of the primary pneumatics admit 85 atmospheric air to the striker pneumatics, and at inflated position close the atmospheric air communication and open communication of the striker pneumatics with the exhaust devices through the respective primary 90 pneumatics chambers, the construction in these respects being that which is familiar and well understood and requires no further detail description.

The two sets of striker pneumatics are 100 relatively positioned, as seen in Fig. 1, the principal set being grouped in three banks or levels upon the shelves, 4, and having the thrust pins, 3, extending up under the respective manual keys for encountering the latter 105 back of their fulcrum. The supplemental set of striker pneumatics is located behind the principal set and arranged to act on the manual keys through the medium of levers, 12, which actuate the thrust pins, 3, posi- 110

tioned for acting on the manual keys a little forward of the position of the thrust pins, 3, of the principal set.

From the several primary pneumatic valves of the principal pneumatic action, flexible tubes, 7, extend by any convenient course, avoiding the sounding devices of the piano, to a member, 8, of a coupling mounted on any convenient portion of the piano casing frame, and having one face exteriorly exposed for connection with a counterpart member, 9, of the coupling. Similarly the flexible tubes, 10, from the primary pneumatics of the supplemental action extend by convenient courses to a coupling member, 8^a, identical in construction, except as to the number of tubes which it accommodates, with the member, 8, and similarly mounted upon the piano casing frame and adapted for connection with a counterpart member, 9^a. These couplings, which are in all respects similar, except as to number of tubes which they accommodate, will be hereinafter described in detail. Their purpose is to permit the cabling of the flexible tubes which are to connect the primary pneumatics with the tracker board which is mounted upon an exterior cabinet, as hereinafter described, so that the entire group of tubes thus cabled or aggregated for handling in one operation can be connected quickly to the piano and to the exterior cabinet and as quickly disconnected therefrom, the length of the cable being such as to permit the exterior cabinet to be positioned at any desired distance from or proximity to the piano.

In an exterior cabinet, 15, there are mounted the usual pumbers, 16, principal exhaust chamber or receiver, 17, and supplemental or high-tension exhaust chamber, 17^a, tracker, 18, take-up and music rolls, 22 and 25, and their actuating motor mechanism, 21, all of these elements being of a construction well understood, the tracker having the necessary number of ducts for connection, as hereinafter described, with both the principal and supplemental set of pneumatics above described, and in addition, other ducts for connection with different regulating and controlling pneumatics and the pedal action hereinafter described.

From eighty-eight of the tracker ducts, flexible tubes, 20, lead to a coupling member, 21, mounted on the cabinet casing, 15, said coupling member being similar to the coupling member, 8, already described, which is mounted on the piano case; and from fifty-eight tracker ducts, comprising two groups of twenty-nine each, made up of nineteen at the opposite ends of the first mentioned group of eighty-eight ducts and ten additional at each end out of the eighty-eight, flexible tubes, 23, extend to a coupling member, 24, precisely similar to the

coupling member, 21, and similarly mounted on the cabinet casing, 15. Both of said coupling members, 21 and 24, are exteriorly exposed for connection to them, respectively, of cables hereinafter described, which consist of flexible tubes extending from the piano case to the exterior cabinet for connecting the tracker in the cabinet with the pneumatic actions in the piano case. From the principal exhaust chamber, 17, a tube, 26, leads to the center of the coupling member, 24, and from the supplemental or high tension exhaust chamber, 17^a, a tube, 27, leads to the center of the coupling member, 21. Similarly, from the coupling member, 8^a, a tube, 27^a, leads to the primary pneumatic chamber of the supplemental action, and from the coupling member, 8^a, on the piano frame a flexible tube, 27^a, leads to the primary pneumatic chamber of the principal action. The reason for thus transposing the main air tubes of the two actions in connecting them with the coupling members, respectively, is that the main air tube, 26, from the principal exhaust chamber is necessarily larger than the main air tube, 27, from the supplemental exhaust chamber, because in the principal action supplied by the first mentioned tube, there will usually be several notes sounded simultaneously, requiring a large air supply for operating the pneumatics, whereas in the supplemental or solo action there will usually be only a single note sounded at a time, calling for a correspondingly smaller air supply to operate the pneumatics; but on the other hand, the number of flexible tubes of the principal action is very much larger than the number of tubes of the supplemental air solo action. By assembling the larger group of small pneumatic tubes with the smaller main air tube and the smaller group of small pneumatic tubes with the larger main air tube, the two couplings and the two cables are made substantially the same size. The transposition indicated avoids making one exceedingly large cable and one comparatively small one, and causes the two cables to be substantially the same size, for, as in the case of the couplings, the larger main air tube which connects the principal action with the principal exhaust chamber is placed in the cable with the smaller number of flexible tubes of the supplemental action, and the smaller main air tube which connects the primary pneumatic chamber of the supplemental action with the supplemental exhaust chamber in like manner are placed in the chamber with the larger number of flexible tubes of the principal action. Controlled by primary pneumatics in the supplemental action chamber, there are provided motor pneumatics, 30, 31 and 32 which are conveniently located at the left-hand end of the group of motor pneumatics of the

supplemental action. Said motor pneumatics, 30, 31 and 32, are for operating, respectively, the soft pedal action, the loud pedal action and the sostenuto pedal action of the piano. The construction and operation of these motor pneumatics and their respective primaries, is that which is shown in my Patent No. 1,005,771, dated November 10, 1911, and need not be herein described further than to state that they are two primaries for controlling each of the motor pneumatics, one of said primaries operating when its connection at the tracker is open to collapse the motor pneumatic to be expanded. For each of these motor pneumatics, therefore, there are two flexible tubes leading to the coupling member, 8^a. The tubes, 30^a and 30^b for the pneumatic, 30; 31^a and 31^b for the pneumatic 31, and 32^a and 32^b for the motor pneumatic, 32.

Three ducts, 40, 41 and 42 near the left-hand end of the tracker, and three ducts, 40^a, 41^a and 42^a, near the right-hand end of the tracker having corresponding flexible tubes, 43^a, 43^b and 43^c; and 43^d, 43^e and 43^f, leading to the coupling, 24, for communicating with the tubes, 30^a, 31^a and 32^a, and 30^b, 31^b and 32^b, above described, for controlling the collapse and extension of the motor pneumatics, 30, 31 and 32. By this construction, the note sheet traveling over the tracker on the cabinet, being provided with perforations corresponding to the three tracker ducts, 40, 41 and 42 at the left-hand, and with the three ducts, 40^a, 41^a and 42^a at the right-hand portion of the tracker, controls the pedal actions of the piano for producing the effects which are produced in personal playing by the foot of the operator depressing and releasing said pedals, respectively. The particular mechanism by which these pneumatics, 30, 31 and 32 operate the several pedal actions referred to will be adapted to the particular character of the respective pedal actions of the piano in each instance, and the details of these connections about to be described, are merely illustrative and not essential.

From the motor pneumatic, 30, a link, 30^c, extends to the arm, 30^a, of the rock shaft, 30^b, which it may be understood has another arm, not shown, suitably connected with the manual base-board, T, which is movable in the customary manner for shifting the hammers for soft action. The connections for operating the board by the rock shaft are not shown.

From the motor pneumatic, 31, a link, 31^c, extends to an arm, 31^a, of the damper rocker bar, 31^b, for rocking said bar in the manner in which it is operated by the loud pedal connection, not shown, except as to the thrust rod, 30^c, which directly actuates said rocker bar.

From the motor pneumatic, 32, the link,

32^c, extends to one of the side arms, 32^a, of the sostenuto lock bar, 32^b, for operating said bar in the manner in which it is operated by the sostenuto pedal connections, not shown, except as to the link, 32^c, which it may be understood is operated by connections with the sostenuto pedal, not shown.

It may be understood that in the exterior cabinet, and connected with the mechanism therein, there may be provided any customary devices for controlling at will, or automatically, the tempo, or the air tension of the exhaust chambers, and these devices are not illustrated nor described because they may be the same as in any auto-pneumatic player mechanism, whether interior or exterior to the piano case.

In order to facilitate connecting the piano by means of the cable with the exterior cabinet located at either side of the piano, it is preferable to mount the coupling members, 8 and 8^a, to which the flexible tubes from the pneumatic actions extend, so as to permit it to turn to face either side or the rear of the piano, and for this purpose it is preferably mounted as shown upon an arm, 50, pivoted on any convenient fixed support, as far forward as such support can be conveniently found, and somewhat preferably upon the pneumatic action, for which purpose a bracket, 51, is mounted upon the rear side of the primary pneumatic chamber of the supplemental action. In order to carry the coupling and tubes and cables attached to it securely at the end of this swinging arm, 100 there may be provided a segmental track, 52, upon which the rear end of the arm rests and travels when it is moved by swinging about the fulcrum to carry the coupling from one side to the other.

The cables extending from the piano to the cabinet which contains the tracker and roll-operating mechanism corresponds to the coupling members already described. Cable, X, comprises fifty-eight small tubes, x, of which fifty-two are for the solo action and six for the pedal action, and a large tube, X¹, which makes junction at the respective couplings with the tubes, 26 and 26^a, of the cabinet and piano, respectively. The cable, Y, 115 comprises eighty-eight small tubes, y, and a larger tube, y¹, not so large as the tube, x, which makes junction at the respective couplings with the tubes, 27 and 27^a, of the cabinet and piano, respectively. The coupling 120 members terminating the cables at the cabinet-connected end are indicated by numerals, 24^a and 21^a, respectively.

All the coupling members, both those which terminate the cables and those which are mounted on the cabinet and piano, respectively, are similarly constructed in this: That each of them consists in a flat plate provided with as many apertures as the number of tubes to be connected with it, the 130

plate having at one side nipples 24^b extending from the respective apertures to receive the flexible tubes, respectively, and being at the other side perfectly flat for abutting 5 upon the correspondingly flat face of the counterpart coupling. Preferably, the abutting faces of the two members are provided with a surface covering, 39, of any slightly compressible material, as thin leather, so 10 that an air-tight junction is effected between the two plates when they are pressed together, and for registering the two plates so that the corresponding tubes will be in proper communication through said coupling members, one member at each junction has dowel projections, 35, and the opposite member at such junction has corresponding dowel sockets, 36, for receiving the dowel pins, thus insuring the accurate 15 registration of the two members with each other when connected. The two dowel pins and the corresponding dowel apertures should be positioned so that they cannot be engaged transposedly; as, for example, by 20 locating them at a different distance from the center, as seen in Fig. 6. For connecting and clamping the two coupling members together at each junction, there may be employed a flange ring, M, having its flange 25 engaged behind the peripheral margin of one of the coupling members (see Figs. 6 and 7), and having any convenient number of oblique slots, m, opening through its unflanged edge to receive and engage studs, m¹, 30 which project from the periphery of the counterpart member, forming a so-called "bayonet lock" device; and for readily engaging and clamping and disengaging this 35 ring to unite and separate the coupling members, the ring may be provided with handles, M¹. (See Fig. 5.)

For positioning the cabinet at any considerable distance from the piano, two more cables may be employed coupled together 45 by the coupling devices; and in order to render this convenient, the coupling members at the opposite ends of the cable are counterparts;—that is, one of them retains the coupling ring, M, and has the dowel apertures, 36, and the other has the pins, m¹, 50 and the dowels, 35; and of the coupling members mounted on the piano case and exterior cabinet, respectively, one is of one form and the other of the other form, as 55 illustrated, so that either one cable or several cables of identical construction coupled together may readily be employed for connecting the exterior cabinet with the piano.

I claim:—

60 1. In combination a piano having mounted on its case striker pneumatics for operating the several sounding devices of the piano, a primary pneumatic chamber, flexible tubes for controlling the several striker pneumatics, and a main exhaust tube lead-

ing from the primary pneumatic chamber; an exterior cabinet, and mounted therein a tracker, exhaust devices, note-sheet-playing mechanism; tubes from the tracker ducts respectively, and a main tube from the exhaust devices; a coupling member mounted on the piano case to which the first-mentioned flexible tubes and the main exhaust tube mentioned are connected; a coupling member mounted on the cabinet to which the flexible tubes and the main air tube mentioned in said cabinet are connected, said coupling members on the cabinet and on the piano case being exteriorly exposed for connection with a counterpart, and a cable comprising flexible tubes and a main air tube and having its opposite ends provided with coupling members which are counterparts of the coupling members on the piano case and the exterior cabinet respectively, and to which said flexible tubes and main air tube are connected at their opposite ends respectively, and means for connecting said cable coupling members with the coupling members on the piano case and cabinet, respectively. 70 75 80 85 90

2. In combination with a piano having mounted on its case striker pneumatics for operating the several sounding devices of the piano, a primary pneumatic chamber, flexible tubes for controlling the several striker pneumatics, and a main exhaust tube leading from the primary pneumatic chamber; an exterior cabinet, and mounted therein a tracker, exhaust devices, note-sheet-playing mechanism, tubes from the tracker ducts respectively, and a main tube from the exhaust devices; a coupling member to which the first-mentioned flexible tubes and the main exhaust tube are connected; a coupling member to which the flexible tubes and the main air tube mentioned in said cabinet are connected, said coupling members being exteriorly exposed for connection with a counterpart and being counterparts, and having the tube mouths of their respective abutting faces arranged for registration of the corresponding mouths, and means for clamping said couplings together. 95 100 105 110 115

3. In combination with a piano having mounted on its case an exhaust chamber, striker pneumatics for operating the respective sounding devices of the piano, flexible tubes controlling said striker pneumatics respectively, and a main air tube leading to the exhaust chamber; an exterior cabinet and portions of automatic player mechanism therein comprising exhaust devices and a main air tube therefrom, a tracker and flexible tubes leading from the respective ducts thereof, a coupling device for connecting the first-mentioned flexible tubes and main air tube with the flexible tubes and main air tube of the cabinet, said coupling device consisting of two plates adapted to abut face 120 125 130

to face, and having correspondingly arranged apertures and nipples surrounding said apertures on the outer side of the plate for receiving the tubes; means for registering said plates with each other for causing their corresponding apertures to coincide, and means for clamping the plates together when thus registered.

4. In combination with a piano having on its case a principal pneumatic action and a supplemental pneumatic action, each comprising a primary pneumatic chamber; a main air tube to said primary pneumatic chamber and a group of flexible tubes for controlling the respective striker pneumatics; a coupling to which the principal action flexible tubes are connected, and a second coupling to which the supplemental action flexible tubes are connected, the main air tube from the supplemental action primary chamber being connected to the first-mentioned coupling, and the main air tube from the principal action primary chamber being connected to the second-mentioned coupling; an exterior cabinet and portions of an automatic player mechanism therein comprising principal and supplemental exhaust devices for the principal and supplemental actions respectively; a tracker, flexible tubes leading from the respective ducts thereof for connection with said actions respectively, and main air tubes leading from the principal and supplemental exhaust devices respectively; a coupling device for connecting the flexible tubes from the tracker pertaining to the principal action with the corresponding tubes from said principal action; a second coupling device for connecting the flexible tubes from the tracker pertaining to the supplemental action with the corresponding flexible tubes from said supplemental action, the main air tube from the principal exhaust chamber being connected with the coupling which receives the supplemental action tracker tubes, and the main air tube from

the supplemental exhaust device being connected with the coupling which receives the principal action tracker tubes, and cables connecting the corresponding couplings on the piano case and exterior cabinet, each comprising main air tubes and groups of flexible pneumatic tubes corresponding to the tubes connected with said couplings respectively.

5. In combination with a piano having mounted on its case a pneumatic action for operating upon the manual keys; flexible tubes leading from the pneumatic action, and a coupling device to which such tubes are connected; a support for the coupling device comprising an arm pivoted on the piano case for swinging its free end horizontally from a position near one side to a position near the other side of the piano case at the rear of the manual, said coupling device being mounted on said free swinging end of said arm.

6. In combination with a piano having mounted on its case a pneumatic action for operating upon the manual keys; flexible tubes leading from the pneumatic action, and a coupling device to which such tubes are connected; a support for the coupling device comprising an arm pivoted on the piano case for swinging its free end horizontally from a position near one side to a position near the other side of the piano case at the rear of the manual, said coupling device being mounted on said free swinging end of said arm, and a track for supporting said free swinging end of said arm mounted on the under side of the piano case and curved about the pivot of the arm.

In testimony whereof I have hereunto set my hand at Chicago, Illinois, this 14th day of May, 1912.

MELVILLE CLARK.
